TRANSFER MECHANISM FOR CALCULATING MACHINES

Daniel Broido, Barnet, England

Application December 26, 1951, Serial No. 263,177
In Great Britain January 2, 1951

6 Claims. (Cl. 235—133)

1

This invention relates to adding, accounting, calculating and like machines, and more specifically to tens transfer or carry devices of the totalizers employed in such machines.

In order to speed up the operation of such devices it has been previously suggested to use a method known as Plus One Minus One. In a mechanism based on this method, unity is added in all orders of the totalizer simultaneously after an additive value-entering operation; then unity is subtracted simultaneously in all orders which do not require a carry. After a subtractive value-entry, unity is subtracted in all orders, and then added in those orders which do not require a carry. In a mechanism of this type the carry can be effected faster than in the conventional staggered type carry devices, which require a timed sequence of carries from the lower orders to the higher orders of the totalizer.

This invention contemplates a method of simultaneous carry in all totalizer orders in a manner which is faster and more convenient than that of the Plus One Minus One method. This novel method provides means for checking the totalizer orders which require a conditional carry after a value-entering operation; thus, it may be conveniently termed the Check method of carry.

In particular, this invention contemplates a method of simultaneous carry suitable with but few minor alterations both for machines of the type referred to wherein digital values 0 to 9 are entered into various totalizer orders during the value-entering operation in a conventional manner, and also for machines of the type referred to wherein the digital values to be entered into various totalizer orders are each increased by unity, for instance as described in the specification to my co-pending application No. 263,176.

The main object of this invention is to provide a carry device which is relatively simple in construction and speedy in operation.

Another object is to provide a method and means for effecting the carry by one single operation simultaneously in all totalizer orders.

More specifically, an object of the invention is to provide means for checking the totalizer orders which stand either at 9 or at 0 after a value-entering operation, according to whether this operation was additive or subtractive, and thus require a conditional carry.

Another specific object is to provide storage means for definite carry impulses, and means for interlocking the storage means of adjacent totalizer orders.

2

An object of the present invention is to provide a carry device suitable, with but minor adjustments, both for totalizers which receive true values and for totalizers which receive values increased by unity.

Other objects will become apparent as the description proceeds.

With these objects in view, a method of carry according to the present invention comprises a storage of definite carry impulses produced during a value-entering operation, a check of totalizer orders which have to transmit these definite carry impulses, and a simultaneous application of a one-step movement to all totalizer orders 15 which require a carry, in a direction depending on whether the value-entry was additive or subtractive.

Means for carrying this method into effect comprise, in operative association with each totalizer order, carry storage means operable when the associated order moves from 9 to 0 in addition and from 0 to 9 in subtraction, check means operable after a value-entering operation for indicating whether the associated order stands at 25 9 or 0, depending on the direction of the value-entry, interlock means controlled by said check means for interlocking the said carry storage means of adjacent orders, and driving means controlled by the said carry storage means for 30 driving the individual totalizer orders simultaneously one step in the direction depending on that of the value-entry.

Considering first an additive value-entering operation:

$$\begin{array}{r}
 9 & 0 & 9 & 9 & 9 \\
 + & & & & 2 \\
 \hline
 9 & 1 & 0 & 0 & 1
 \end{array}$$

it is evident that the units order has produced a 40 definite carry impulse; it may be termed a Sending order. The tens order may be termed a Transmitting order; it has produced a carry impulse merely due to the fact that it is next-higher to a Sending order. Similarly, the hundreds order is a Transmitting order; it has produced a carry impulse because it is chain-higher to a Sending order (units). It may be stated that if an order stands at 9 after an additive value-entry, it is a Transmitting order; it produces a carry impulse conditional on this order being chain-higher or next higher to a Sending order.

Similarly, when an order moves from 0 to 9 during subtraction, it produces a definite carry impulse and may be termed a Sending order. 55 An order which stands at 0 after a subtractive value-entry may be termed a Transmission or-

der; it produces a carry impulse conditional on this order being chain-higher or next-higher to a Sending order.

The present check method of carry contemplates an arrangement whereby the definite carry impulses produced during a value-entering operation are stored; after the value-entering operation all totalizer orders are checked to determine which are Transmitting orders and which Transmitting orders are next-higher or chain-higher to Sending orders; the carry is effected simultaneously in all orders which receive a definite carry impulse (from a Sending order) or a conditional carry impulse (from a Transmitting order chain-higher to a Sending order), by moving these orders one step in the required direction.

Thus, the above example may be treated as follows:

$$\begin{array}{r}
 9\ 0\ 9\ 9\ 9 \quad \text{Totalizer stand before value-entry.} \\
 + \quad \quad \quad \quad \quad 2 \quad \text{Value-entering operation.} \\
 \hline
 9\ 0\ 9\ 9\ 1 \quad \text{Totalizer stand after value-entry.} \\
 t \quad t \quad t \quad s \quad \text{Check (t=Transmitting order, s=} \\
 \quad \quad \quad \quad \quad \text{Sending order).} \\
 + \quad 1\ 1\ 1 \quad \text{Carry operation.} \\
 \hline
 9\ 1\ 0\ 0\ 1 \quad \text{Totalizer stand after carry.}
 \end{array}$$

In subtraction the operation may be as follows:

$$\begin{array}{r}
 1\ 0\ 9\ 0\ 0 \quad \text{Totalizer stand before value-entry.} \\
 - \quad \quad \quad \quad \quad 2 \quad \text{Value-entering operation.} \\
 \hline
 1\ 0\ 9\ 0\ 8 \quad \text{Totalizer stand after value-entry.} \\
 t \quad t \quad t \quad s \quad \text{Check.} \\
 - \quad 1\ 1 \quad \text{Carry operation.} \\
 \hline
 1\ 0\ 8\ 9\ 8 \quad \text{Totalizer stand after carry.}
 \end{array}$$

Considering now the arrangement whereby the digital values to be entered into various totalizer orders are each increased by unity, it will be seen that the carry must take place in reverse; that is, after a value-entering operation those orders which do not require a carry must be moved one step in the direction opposite to that of the value-entry.

Considering the above additive example, the procedure is as follows:

$$\begin{array}{r}
 9\ 0\ 9\ 9\ 9 \quad \text{Totalizer stand before value-entry.} \\
 + \quad 1\ 1\ 1\ 1\ 3 \quad \text{Value-entering operation (actual} \\
 \quad \quad \quad \quad \quad \text{value: 2).} \\
 \hline
 0\ 1\ 0\ 0\ 2 \quad \text{Totalizer stand after value-entry.} \\
 t \quad t \quad t \quad s \quad \text{Check (t=Transmitting order, s=} \\
 \quad \quad \quad \quad \quad \text{Sending order).} \\
 - \quad 1\ 0\ 0\ 0\ 1 \quad \text{Carry operation.} \\
 \hline
 9\ 1\ 0\ 0\ 1 \quad \text{Totalizer stand after carry.}
 \end{array}$$

Considering the above subtractive example, the procedure in the case of totalizers which receive values increased by unity is as follows:

$$\begin{array}{r}
 1\ 0\ 9\ 0\ 0 \quad \text{Totalizer stand before value-entry.} \\
 - \quad 1\ 1\ 1\ 1\ 3 \quad \text{Value-entering operation (actual} \\
 \quad \quad \quad \quad \quad \text{value: 2).} \\
 \hline
 0\ 9\ 8\ 9\ 7 \quad \text{Totalizer stand after value-entry.} \\
 t \quad t \quad s \quad \text{Check.} \\
 + \quad 1\ 1\ 0\ 0\ 1 \quad \text{Carry operation.} \\
 \hline
 1\ 0\ 8\ 9\ 8 \quad \text{Totalizer stand after carry.}
 \end{array}$$

It will be seen that in the case of totalizers which receive values increased by unity a Sending order is one which has moved, in addition, from 9 to 0 and beyond, while a Transmitting order is one that has moved from 9 to 0 and has remained at 0. Similarly, in subtraction a Send-

ing order has moved from 0 to 9 and beyond, while a Transmitting order has moved from 0 to 9 but not beyond.

The present invention will now be described, 5 firstly as applied to totalizers which receive values increased by unity, and secondly as modified to suit totalizers which receive true values.

In the accompanying drawings illustrating a preferred embodiment of the present invention:

10 Figure 1 is a vertical section, taken substantially on line I—I of Figure 2, showing the carry device in an inoperative or non-carrying position,

15 Figure 2 is a vertical section substantially on line II—II of Figures 1 and 6,

15 Figure 3 is a view in the direction of arrow III in Figure 1, the machine cover being removed,

20 Figure 4 is a section similar to Figure 1 but showing the carry device in the carrying position,

20 Figure 5 is a vertical section substantially on line V—V of Figure 2, showing part of the operating mechanism,

25 Figure 6 is a vertical section substantially on line VI—VI of Figure 2, showing another part of the operating mechanism, and

25 Figure 7 is a section similar to that of Figure 1 but showing a modified carry device.

Referring to Fig. 1, the totalizer wheels 10 are 30 rotatably mounted on a shaft 11 suitably supported in the machine structure 12, 13, Fig. 2; they are visible through suitable apertures in the machine cover 14, Figs. 1 and 4. Fixed to each totalizer wheel 10 is a pinion 15 and a carry lug 35 16. Each pinion 15 meshes with a gear 17 rotatable on a shaft 18 fixedly supported in the machine structure. Gears 17 are operatively associated with differentially displaceable racks 20 more fully described in the specification to my co-pending patent application No. 263,176. It is sufficient to state here that racks 20 are movable by springs 19 in guides 21, 22, 23, 24 under the control of a drive bar 25 which normally holds the racks in a retracted position shown in Fig. 1.

40 When the drive bar 25 moves to the left as viewed in Fig. 1, each spring 19 pulls its associated rack 20 to the left until its tip 26 abuts against one of the stops of a set generally indicated at 0-9. Each of the stops 0-9 is individually and selectively settable or movable into the path of the associated rack 20, and each stop is so positioned and dimensioned that the distance between the stop and the tip 26 of rack 20 is equal to the digit associated with the stop plus unity. Thus, there

45 55 is a gap equal to one rack step (which is proportionate to the spacing of the totalizer wheels 10) between the 0 stop and the tip 26 of rack 20 when the latter is in the retracted position; the distance between the 1 stop and the rack is equal to two rack steps, and so on, the distance between the 9 stop and the end of rack being equal to ten rack steps. Thus, when a rack 20 moves from its retracted position onto one of stops 0-9, the rack movement is representative of the value asso-

60 65 ciated with the respective stop plus unity.

Means for selectively setting stops representative of various digital values are well known in the art; for instance, reference may be had to my British patent specification No. 577,330.

70 75 Idler gears 27 rotatably mounted on a shaft 28 secured in a support 29 serve to interconnect the racks 20 with the gears 17. As shown in Fig. 2, the width of an idler 27 is substantially equal to the combined width of a rack 20 and gear 17.

75 Prior to an additive value-entering operation the

idler shaft 28 is raised so as to mesh the idlers 27 with the associated gears 17 and racks 20; when the drive bar 25 moves to the left as viewed in Fig. 1, racks 20 rotate their idlers 27, and each idler drives the associated gear 17 and totalizer wheel 10 through a distance representative of the respective stops 9-9 plus unity, whereby the totalizer wheels 10 are rotated additively in the anti-clockwise direction. At the end of forward stroke of bar 25 the idler shaft 28 is lowered, so that idlers 27 are demeshed from racks 20 and gears 17; as now the drive bar 25 is moved to the right as viewed in Fig. 1, it restores the racks 20 to their retracted position while the totalizer wheels 10 remain stationary.

During a subtractive value-entering operation the idler shaft 28 is not raised until the drive bar 25 reaches the end of its forward stroke; only then are the idlers 27 meshed with gears 17 and racks 20, so that the totalizer wheels 10 are rotated subtractively in the clockwise direction during the return stroke of racks 20.

A carry pawl 30 rockable on shaft 18 is associated with each carry lug 16, on to which it is biased by a spring 31. An arm 32 on each carry pawls 30 co-acts with a storage plate 33 rockable on shaft 34 fixedly supported in the machine structure. Each storage plate 33 has a lug 35 supporting the end of a striker 36 rockable on shaft 37 secured in a support 38. Each striker 36 is biased by a spring 39 and presses the associated storage plate 33 towards a restoring bar 40; however, storage plates 33 are normally latched by arms 32 of carry pawls 30. If a totalizer wheel 10 moves from 9 to 0 during addition, or if it moves from 0 to 9 during subtraction, its carrying lug 16 causes the associated carry pawl 30 to rock anti-clockwise, and the arm 32 delatches the associated storage plate 33 which rocks slightly clockwise on to restoring bar 40 due to spring 39. In this manner, carry impulses received from Sending and Transmitting orders are stored.

As previously explained, it is necessary to differentiate between Sending orders (that is, totalizer wheels 10 which have moved from 9 to 0 and beyond in addition or from 0 to 9 and beyond in subtraction) and Transmitting orders (that is, totalizer wheels which have moved from 9 to 0 and have remained at 0 during addition, or from 0 to 9 and have remained at 9 during subtraction). To this end, each totalizer wheel 10, except that of the lowest order, is associated with a check rocker 41 mounted on a shaft 42 slidably and rockably supported in the machine structure. Each rocker 41 is biased by a torsion spring 43 towards the respective totalizer wheel 10; one end of the spring passes through a hole in the hub 44 of the rocker and is secured in a hole of shaft 42, thus normally preventing the rocker from touching the totalizer wheel. A recess 45, Fig. 3, is provided on the right-hand side of the rim of each totalizer wheel 10 in such an angular position that it is located opposite the end of check rocker 41 when the wheel is at 0. A similar recess 46 is provided on the left-hand side of each totalizer wheel in angular alignment with the check rocker when the wheel is at 9. After an additive value-entry the check shaft 42 is axially located, in a manner to be described in due course, so that the check rockers 41 are aligned with the "0" recesses 45, as shown in dotted lines in Fig. 3, whereupon the shaft is rocked anti-clockwise as viewed in Fig. 1; if a rocker finds a recess, it rocks into it, otherwise

the rocker does not rock appreciably, being arrested by the circumference of the totalizer wheel 10. Similarly, after a subtractive value-entry the check shaft 42 is shifted so that the check rockers 41 are transversely aligned with the "9" recesses 46, as shown in full lines in Fig. 3; when the shaft is rocked anti-clockwise those rockers which are angularly aligned with recesses 46 rock out appreciably while the other rockers remain substantially stationary. In this manner, rockers 41 check the positions of the associated totalizer wheels 10 and ascertain which wheels stand at 0 after an additive value-entry or at 9 after a subtractive value-entry, that is, which wheels belong to Transmitting orders.

Each check rocker 41 has a pin 47 co-acting with a latch 48 rockable on a shaft 49 fixedly supported in the machine structure. Each latch 48 is biased by a spring 50 into engagement with a trigger 51 rockable and slidable on a shaft 52 fixed in the machine structure. Normally each latch 48 latches its associated trigger 51 in the position shown in Fig. 1. However, if the respective check rocker 41 has rocked out during the checking operation just described, pin 47 has caused its latch 48 to delatch its trigger 51, which now swings anti-clockwise due to its spring 53 into position indicated in Fig. 4. Immediately after the checking operation the check shaft 42 is restored clockwise, thus restoring the check rockers 41, whereby pins 47 allow the latches 48 to return to their normal position; however, previously delatched triggers 51 remain in the delatched position for the purpose presently to be described.

As previously stated, it is necessary to differentiate between those Transmitting orders which are chain-higher to a Sending order and those which are not; this differentiation is effected by triggers 51, each of which has a nose 54 co-acting with a lug 55 on the associated storage plate 33 and with a lug 56 on the storage plate 33 of the next-lower order. Lugs 55, 56 are arranged axially adjacent each other on storage plates 33 of adjacent orders, a trigger 51 being of a width substantially equal to the combined width of two adjacent lugs 55, 56, as clearly shown in Fig. 2. There is an angular gap between the associated lugs 55, 56, as clearly shown in Fig. 1, the nose 54 of each trigger 51 being normally positioned just above this gap. On being delatched by its latch 48, a trigger 51 rocks as described, so that its nose 54 enters the gap between lugs 55, 56 on associated storage plates 33 of adjacent orders, as shown in Fig. 4. Thus, triggers 51 establish a chain or cross-connection between adjacent totalizer orders.

After the checking operation of rockers 41 the storage restore bar 40 is caused to move clockwise, by means to be described in due course, and in consequence some of storage plates 33 also rock clockwise due to springs 39, namely those storage plates which (a) have been previously delatched by their carry pawls 30 and (b) are not prevented from doing so by their triggers 51. Indeed, if a trigger 51 has interposed its nose 54 between lugs 55, 56 of two adjacent storage plates 33, the storage plate of the higher order can rock into position indicated in Fig. 4 only if the storage plate of the next-lower order rocks, too. However, if the storage plate of the next-lower order does not rock, because it does not belong to a Sending order and has not been delatched during the value-entering operation, then the trigger 51 prevents the storage plate 33

of the next-higher order from rocking and this plate, although delatched, remains substantially stationary in the position of Fig. 1. If a number of adjacent storage plates 33 belong to Transmitting orders, they will all be interconnected by their triggers 51 as described. It will be noted that the storage plates 33 and the strikers 36 of all totalizer orders which require a carry rock out when the restore bar 40 is rocked clockwise, while the storage plates and strikers of all orders which do not require a carry remain substantially stationary.

Each gear 17, except that of the units order, coacts with a gear segment 57 rockable on a shaft 58 secured in a support 59; each segment 57 is located by a ball 60 biased by a spring 61. Prior to the carry operation the gear segment support 59 and the idler gear support 29 are so moved, by means to be described in due course, that the gear segments 57 are meshed with, and the idler gears 27 are demeshed from, the gears 17 driving the totalizer wheels 10.

Each gear segment 57 has a stud 62 normally located in a grooved pawl 63 rockable on shaft 31 in association with a striker 36. If a striker 36 has not rocked out as described and has remained in the position shown in Fig. 1, stud 62 remains in engagement with the pawl 63 even after the respective gear segment 57 has moved into mesh with its gear 17. However, if the striker is associated with a totalizer order requiring a carry and has rocked as described into position shown in Fig. 4, then the pawl 63 clears the stud 62 when the associated gear segment 57 is meshed with gear 17. Thus, after the gear segments 57 have been meshed with gears 17, the segments remain in operative connection with pawls 63 only in those totalizer orders which do not require a carry.

At the end of an additive operating cycle the striker support 38 is moved, by means to be described in due course, substantially downwards. Thereby those striker pawls 63 which have remained in engagement with their gear segments 57 cause the latter to rock clockwise and to advance the respective totalizer wheels 10 one step clockwise, that is subtractively. In this manner the unity entered into all totalizer orders during the value-entering operation in excess of the actual amount to be added is now subtracted, as a carry is not required in these orders. Those pawls 63 which have been previously disengaged from their gear segments 57 move down idly; unity is not subtracted in these totalizer orders, that is, the carry is effected.

Similarly at the end of a subtractive cycle the striker support 38 is moved upwards, and those striker pawls 63 which have remained in engagement with studs 62 on gear segments 57 rock the latter one step anti-clockwise and thus advance the respective totalizer wheels 10 anti-clockwise, that is additively, in order to cancel the unity previously entered into these orders in excess of the actual amount to be subtracted, as a carry is not required in these orders. Those striker pawls which have been disengaged from their gear segments move up idly and the excess unity remains in these orders, thus effecting the carry.

Prior to the next value-entering stroke of racks 20 the storage restore bar 40 moves anti-clockwise and restores the storage plates 33, the strikers 36, and the pawls 63, whereupon the gear segments 57 are demeshed from gears 17; studs 62 on previously rocked gear segments re-engage their associated pawls 63. Prior to the next carry op-

eration the striker support 38 is restored to its normal position, thus restoring the strikers 36, the striker pawls 63, and the previously rocked gear segments 57. Each striker pawl 63 is connected to its associated striker 36 by a spring 64. If a gear segment 57 has remained stationary during the carry stroke of strikers 36, the respective pawl 63 during return stroke rocks out slightly, whereupon the spring 64 causes the pawl to re-engage the stud 62 of the gear segment.

It may happen that a totalizer wheel 10 actuates its carry pawl 30 during the carry stroke of strikers 36; this would delatch the associated storage plate 33 and the striker pawl 63 would drop out of engagement with stud 62 before the completion of the one-step movement of gear segment 57. In order to prevent this occurrence, each striker 36 is provided with a slot 65 engaged by a lug 66 of a rocker 67 mounted at 68 and normally maintained in the position shown in Figs. 1 and 4 by a spring 69 anchored in a block 70. Slots 65 are so shaped that before the carry stroke starts the strikers 36 can rock freely into "carry" position shown in Fig. 4; springs 69 permit their rockers 67 to follow the subsequent movement of strikers 36. However, if a striker 36 has remained in the "no-carry" position of Fig. 1, its rocker 67 will prevent a rocking movement of the striker during the carry stroke of striker support 38.

The storage restore bar 40 restores the storage plates 33 sufficiently for carry pawl arms 32 to latch the storage plates, whereupon it moves slightly back into position shown in Fig. 1. As the storage plates 33 are being restored, they shift across the trigger shaft 52 those triggers 51 which have previously been in action, whereupon a trigger restore bar 71 restores these triggers slightly beyond their normal position and then moves slightly back, so that the triggers are latched by the check latches 48.

The clearing device for the totalizer does not form a part of the present invention. Briefly, it may comprise a number of studs 72 fixed to gears 17 in evenly spaced positions, the distance between two adjacent studs 72 corresponding to a full turn of totalizer wheel 10. A clearing bar 73 rotatable and radially shiftable on shaft 18 has grippers 74 adapted to cooperate with studs 72. When the clearing bar 73 is rotated anti-clockwise (by means not shown), it is first caused to move slightly towards the shaft 18, so that each gripper 74 is interposed in the path of studs 72 on the associated gear 17. On continued rotation of bar 73 the grippers 74 engage the nearest studs 72 and rotate the gears 17 and the totalizer wheels 10 into the zero position; whereupon the clearing bar 73 is restored, preferably by a spring. Prior to rotation of bar 73 the storage restore bar 40 is caused to restore the storage plates 33, and the gear segment support 59 is moved to demesh the gear segments 57 from gears 17, whereupon a crossbar 75 is lowered to lock the carry pawl arms 32, so that any overthrow of totalizer wheels 10 may be prevented by carry pawls 30 engaging the carry lugs 16. After clearing the cross bar 75, the storage restore bar 40, and the gear segments 57 are restored to their normal positions.

70

Operating means

The machine is operated by a main driving shaft 76, Fig. 2, suitably journaled in machine frame 77, 12 and rotated once during each op-

erating cycle by a suitable handle or motor (not shown).

Referring to Figs. 2 and 5, the mesh-demesh operation of idler gears 27 and gear segments 57 is controlled by a grooved cam 78 fixedly mounted on main shaft 76. Cam 78 coacts with a roller 79 journalled in a follower 80 fixedly mounted on a shaft 81 journalled in machine frame 77, 82. An arm 83 is fixedly mounted at each end of shaft 81; each arm 83 has a pin-and-slot connection 84 to a lever 85 rockable on a trunnion 86 fixedly supported in machine frames 77, 82, respectively. The idler shaft support 29 is fixed at each end to one of levers 85. Rockable on each trunnion 86 is an arm 87 connected by a spring 88 to the respective lever 85; the gear segment support 59 is fixed at each end to one of arms 87. During addition the main driving shaft 76 is rotated clockwise as viewed in Fig. 5, and early in the cycle the cam 78 causes its follower 80 to rock anti-clockwise, which causes levers 85, arms 87, and supports 29, 59 to rock clockwise around trunnions 86, and thus to mesh the idler gears 27 with, and to demesh the gear segments 57 from, the driving gears 17, as described hereinbefore. The parts remain in this position until shortly before the racks 29 start on their return stroke; now cam 78 restores the follower 80 and supports 29, 59, so that the idler gears 27 are demeshed from, and the gear segments 57 are meshed with, the gears 17. During subtraction the main shaft 76 is rotated anti-clockwise; at about the middle of the cycle cam 78 rocks its follower 80 anti-clockwise, thus meshing the idler gears 27 with, and demeshing the gear segments 57 from, the gears 17. Near the end of cycle cam 78 restores the follower 80 and the supports 29, 59.

Trigger restore bar 71 is operated by a grooved cam 89, Fig. 5, fixed to shaft 76 and co-acting with a roller 90 journalled in a follower 91 rotatable on a sleeve 92 on follower shaft 81. Linked at 93 to the follower 91 is a connecting rod 94 linked at 95 to an arm 96 secured to a sleeve 97 rockable on a shaft 98 journalled in the supporting structure. An arm 99 is fixed at each end of sleeve 97. Linked at 100 to each arm 99 is a connecting rod 101 linked at 102 to a bracket 103 rockable on trigger shaft 52; the trigger restore bar 71 is fixed at each end to one of brackets 103. Rotation of cam 89 in either direction causes its follower 91 to rock anti-clockwise early in the cycle and to swing the trigger restore bar 71 clockwise around the trigger shaft 52, thus restoring the triggers 51; near the end of cycle the cam follower 91 is restored clockwise, thus rocking the trigger restore bar 71 anti-clockwise and releasing the triggers 51 as described.

Storage restore bar 40 is operated by a cam 104, Fig. 2, fixed to the main shaft 76. Cam 104 is somewhat similar in shape to the trigger restore cam 89; it co-acts with a roller 105 journalled in a follower 106 identical in shape with follower 91, Fig. 5. Cam follower 106 is rockable on sleeve 92 on follower shaft 81 and has a pin-and-slot connection 107 to a rod 108 linked to a plate 109 secured to shaft 98 through a suitable hole in sleeve 97. Fixed at each end of shaft 98 is an arm 110 to which is linked at 111 a connecting rod 112 linked at 113 to a bracket 114 rotatable on the storage shaft 34. The storage restore bar 40 is fixed at each end to one of brackets 114. Rotation of cam 104 in either direction causes the storage restore bar 40 to rock anti-clockwise just before the restoring operation of the trigger restore bar 71, and to restore the storage plates 33 75

and the strikers 36 as described; near the end of cycle, just after the release of triggers 51, the storage restore bar 40 rocks clockwise and releases the storage plates 33 and the strikers 36 to effect the carry operation as described.

A spring 115 exerts a bias on the connecting rod 108 towards the cam follower 106. As described above, the storage restore bar 40 is operated to restore the storage plates 33 and the support 59 is operated to demesh the gear segments 57 from gears 17 during the clearing operation, whereupon the storage restore bar 40 and the support 59 are restored by springs 115, 88, respectively.

Striker support 38 is operated during addition by a cam 116 and during subtraction by a cam 117, Figs. 6 and 2, both these cams being rotatably mounted on the main shaft 76. A driver 118 is adapted during additive (clockwise as seen in Fig. 6) rotation of shaft 76 to engage a pawl 119 pivoted at 120 in the "additive" cam 116 and biased by a torsion spring 121 into engagement with driver 118. Cam follower 122 is rockably mounted on sleeve 92 on follower shaft 81; journalled in cam follower 122 is a roller 123 coacting with cam 116. Linked at 124 to the follower 122 is a slide 125 mounted on a guide pin 126. Prongs 127, 128 on slide 125 co-act with pins 129 in a plate 130 secured to a shaft 131 suitably journalled in the supporting structure. Two brackets 132 are secured to shaft 131; the striker support 38 is fixed at each end to one of brackets 132. Spring 133 anchored in the supporting structure maintains the roller 123 in contact with the cam 116.

Between 45° and 90° of an additive cycle cam 116 rocks its follower 122 clockwise, thus causing the slide 125 to move downwards; thereby, one of prongs 127 moves the upper pin 129 downwards until both pins 129 are level, any overthrow being prevented by the other prong 127. This brings the striker support 38 into a neutral position shown in Fig. 1 and in dotted lines in Fig. 6. Assuming the previous cycle was an additive one, pins 129 would have remained in positions shown in Fig. 6, and the downwards movement of slide 125 would rock the brackets 132 clockwise to bring the striker support 38 into the neutral position. If the previous cycle was subtractive, the left-hand pin 129 would remain higher than the right-hand pin 129, and the downwards movement of slide 125 would rotate plate 130 and brackets 132 anti-clockwise. In either case the slide 125 while moving downwards restores the striker support 38 to its neutral position.

Guide pin 126 is fixed in a rocker 134 rotatable at 135 in the supporting structure; rocker 134 has an upper arm 136 with a nose 137 and a lower arm 138 with a nose 139. As will be presently explained, rocker 134 remains after an additive cycle in the position shown in Fig. 6. It is maintained in this position by a detent 140 pivoted at 141 and biased by a spring 142 into engagement with the lower one of two recesses 143 formed in the lower arm 138 of rocker 134. Upper nose 137 co-acts with a pin 144 fixed in the additive cam 116, while the lower nose 139 co-acts with a pin 145 in the subtractive cam 117. At about 90° in an additive cycle the pin 144 approaches the upper nose 137. If the previous cycle was a subtractive one, rocker 134 would be in such a position that the upper recess 143 would be engaged by detent 140; in this case,

pin 144 would now engage the upper nose 137 and rotate the rocker 134 into position shown in Fig. 6. Assuming the previous cycle was additive, pin 144 will just touch the nose 137 without affecting the position of rocker 134 and slide 125.

Near the end of an additive cycle cam 116 allows the cam follower 122 to rock anti-clockwise, thus raising the slide 125; the right-hand prong 128 in slide 125 being aligned with the right-hand pin 129 in plate 130, this prong causes the plate 130 to rotate anti-clockwise, so that brackets 132 lower the striker support into position shown in full lines in Fig. 6. This results in a -1 carry stroke of strikers 36 as described above.

Considering now a subtractive cycle, during which the main shaft 76 is rotated anti-clockwise, a driver 146 fast on the main shaft drives the subtractive cam 117 by means of a pawl 147 mounted in this cam in a manner similar to the mounting of pawl 119 in the additive cam 116. Shortly after one-half of the cycle cam 117 operates roller 123' in cam follower 122 and causes slide 125 to move downwards and to restore the striker support into the neutral position as described. At about 232° pin 145 approaches the lower nose 139 and, if the previous cycle was additive and the parts have remained in the position of Fig. 6, engages the nose 139 and rotates the rocker 134 anti-clockwise, so that detent 140 engages the upper recess 143; thereby the guide pin 126 causes the slide 125 to rock anti-clockwise around its pivot 124, so that now the left-hand prong 128 is aligned with the left-hand pin 129 in plate 130. Near the end of cycle the subtractive cam 117 causes the slide 125 to move upwards, whereby the left-hand prong 128 engages the left-hand pin 129 and rotates the plate 130, shaft 131, brackets 132, and striker support 38 clockwise. In this manner the strikers 36 and pawls 63 effect the +1 carry stroke, as described.

It will be noted that the additive cam 116 is driven only during additive cycles, while the subtractive cam 117 is driven only during subtractive cycles. Suitable means such as spring-loaded detents, not shown, may be provided to prevent inadvertent rotation of cams 116 and 117 during subtractive and additive cycles, respectively.

Operating means for the check rocker shaft 42 will now be described. A double pawl 148 is fixedly mounted on shaft 141 suitably journaled in the supporting structure, a spring 142 tending to rock the pawl 148 towards the main shaft 76. Laterally the pawl is disposed between the striker cams 116, 117, its two prongs being respectively in lateral alignment with a pin 149 fixed in the additive cam 116 (see also Fig. 2) and with a pin 150 fixed in the subtractive cam 117. When either of the cams is rotated, one or the other of pins 149, 150 contacts the associated prong of pawl 148 near the end of cycle, and rocks the pawl and the shaft 141 clockwise, whereupon the pawl and the shaft are restored by the spring 142. This reciprocation of shaft 141 is communicated to an arm 151, Fig. 5, secured to shaft 141 and linked at 152 to a connecting rod 153 linked at 154 to an arm 155 slidably but not rotatably mounted on the check rocker shaft 42. Thus, as the shaft 141 is rotated clockwise and then restored, the rocker shaft 42 is rotated first anti-clockwise and then clockwise, and the checking operation is effected as described above.

As shown in Fig. 6, the upper prong 136 of rocker 134 has a pin-and-slot connection 156 to an arm 157 secured to a sleeve 158 rotatable on shaft 141. Secured to sleeve 158 is a bracket 159, Fig. 5, on which is fixedly mounted a groove cam piece 160 engaged by the lower end 161 of a clutch fork 162 pivotally mounted at 163 in the supporting structure. Forked upper end 164 of clutch fork 162 engages a groove in a clutch disc 165 fixedly mounted on the check rocker shaft 42. Cam piece 160 is so shaped that, as long as the main shaft 76 is rotated additively and the rocker 134 remains in the position of Fig. 6, clutch fork 162 keeps the check rocker shaft 42 shifted axially to the right as viewed in Fig. 3, and check rockers 41 remain laterally aligned with "0" recesses 45 in the totalizer wheels 10, as described. When the main shaft 76 is rotated subtractively, rocker 134 rotates slightly anti-clockwise as viewed in Fig. 6 as previously described, and the resulting clockwise rotation of shaft 141 and cam piece 160 causes the clutch fork 162 to shift the check rocker shaft 42 axially to the left in the sense of Fig. 3, so as to align the check rockers 41 with "9" recesses 46 in the totalizer wheels 10.

Modification

The invention will now be described as applied to totalizers which receive true values, and not values increased by unity as described above with reference to the preferred embodiment.

It will be apparent from a perusal of calculation examples given above that, while in the preferred embodiment the function of check rockers 41 after an additive value-entry is to check which totalizer orders stand at 0, in the present modification their function is to check which orders stand at 9. Similarly, after subtraction the check rockers 41 in the preferred embodiment have to check which totalizer orders stand at 9, whereas in this modification the rockers have to check which totalizer orders stand at 0. Thus, the function of check rockers 41 is reversed in this modification as compared to the preferred embodiment. This reversal of function can be achieved simply by replacing the cam piece 160, Fig. 5, by another cam piece adapted to keep the check rocker shaft 42 during additive revolutions 30 of the main shaft 76 in the left-hand axial position of Fig. 3, so that check rockers 41 are aligned with "9" recesses 46 in the totalizer wheels 10, and during subtractive revolutions of shaft 76 to align the check rockers with the right-hand "0" recesses 45. Alternatively, in this modification the "0" recesses 45 may be arranged on the left-hand side of wheels 10 as viewed in Fig. 3, and the "9" recesses 46 may be arranged on the right-hand side; that is, the axial position 40 of recesses 45, 46 may be reversed as compared to the preferred embodiment.

The modified carry device is shown in Fig. 7, the modified parts similar to those of the preferred embodiment being identified by the same reference numerals with suffix A. Strikers 36A are adapted to co-act with studs 62 on gear segments 57 directly, without the intermediary of pawls 63. There is normally a somewhat larger clearance between the storage plates 33 and the storage restore bar 40. Each striker 36A has a slot 166 which normally engages the stud 62 on the associated gear segment 57. However, when gear segments 57 are meshed with gears 17 as described above, stud 62 moves out of slot 166 50 if the striker 36A remains in the no-carry posi-

tion shown in Fig. 7. If the striker 36A is allowed by its storage plate 33 to rock anti-clockwise around its shaft 37, then the slot 166 remains in engagement with stud 62 even after gear segments 57 have been meshed with gears 17. The carry is effected as in the preferred embodiment by a movement of the striker support 38. In this modification, striker support 38 moves substantially upwards after an additive value-entry and downwards after a subtractive value-entry, so that those strikers 36A which have remained in engagement with their gear segments 57 advance the associated totalizer wheels 10 one step additively or subtractively, respectively.

If a totalizer wheel 10 moves from 9 to 0 in addition, or from 0 to 9 in subtraction, it produces a definite carry impulse which is stored by the action of lug 16 rocking the carry pawl 30, so that its arm 32 unlatches the storage plate 33 which drops on to the restore bar 40; thus, the striker 36A controlled by this Sending order remains in engagement with gear segment 57 of the next-higher order after the meshing of segments 57 with gears 17. Consequently, carry will be effected to the next-higher order by advancing it one step during the carry stroke of strikers 36A, additively after an additive value-entry or subtractively after a subtractive value-entry.

Transmitting orders are checked by rockers 41A which, as already explained, sense the "9" recesses 48 after addition and "0" recesses 45 after subtraction. Each check rocker 41A has an extension 167 which, when the rocker enters a recess 45 or 46, causes the carry arm 32 to delatch its storage plate 33 just after the respective latch 48 has delatched its trigger 51. Thus, when the trigger restore bar 71 releases the triggers 51 as described, the storage plates 33 of those Transmitting orders which are next-higher or chain-higher to a Sending order will rock clockwise and permit their strikers 36A to re-engage their gear segments 57 and to effect the carry. On the other hand the storage plates 33 of those Transmitting orders which are not next-higher or chain-higher to a Sending order will not rock out, being locked by their triggers 51; their associated strikers 36A will not re-engage their gear segments 57 and will not effect a carry in the respective totalizer orders.

It will be noted that in the present modification the direction of the carry stroke of strikers 36A is opposite to that of strikers 36 of the first-described arrangement. This change of direction of striker support 38 can be achieved very easily by arranging the upper prong 136 of rocker 134, Fig. 6, to cooperate with the "subtractive" cam 117, and reversely to arrange the lower prong 133 to co-act with the "additive" cam 116, by securing pins 144, 145 in cams 117, 116, respectively.

It will be seen that the modification just described differs very little from the first-described embodiment, the different action being achieved mainly by a reversed operation of the check rockers 41, 41A and of the striker support 38.

It may be noted that the operation of check rockers 41, 41A, the movement of storage plates 33 and of strikers 36, 36A into the carry position, and the engagement of gear segments 57 with gears 17 can take place immediately on completion of the value-entering operation and while the sensing racks 20 are being demeshed from gears 17. The actual carry operation, namely

the movement of the striker support 38, can be effected very quickly and positively, inasmuch as there is no possibility of a rebound or overthrow.

It will be obvious to those skilled in the art that the carry devices described above may be modified in many respects without departing from the spirit of the present invention.

The invention may be readily applied to direct-multiplying machines of the type requiring two carries during each operating cycle; if required, one carry may be effected additively, and the other carry may be effected subtractively, as described.

What I claim is:

- 15 1. In a machine of the type referred to having a totalizer with a plurality of denominational orders, carry storage means operatively associated with each totalizer order and operable when the associated order moves from 9 to 0 during addition and from 0 to 9 during subtraction, check means operable after a value-entering operation for indicating whether the associated order stands at 9 or 0, depending on the direction of value-entry, interlock means controlled by said check means for interlocking the said carry storage means of adjacent orders, and driving means controlled by said carry storage means for driving the individual totalizer orders simultaneously one step in the direction depending on that of the value-entry.
- 20 2. In a machine of the type referred to having a totalizer with a plurality of denominational orders adapted to receive additive and subtractive digital values each increased by unity, carry storage elements each associated with a totalizer order and operable when the associated order moves from 9 to 0 during addition and from 0 to 9 during subtraction, check elements each associated with a totalizer order and movable into an operative position when the associated order stands at 0 after an additive value-entry and at 9 after a subtractive value-entry, interlock members each movable by an operative check element to lock the said storage element of the associated order to that of the next-lower order, and means for driving all totalizer orders associated with storage elements which were operated during the value-entry and are associated with inoperative check members, and also all totalizer orders associated with storage members, locked to these operated storage elements associated with inoperative check members, substantially simultaneously one step in the direction opposite to that of the value-entry.
- 25 3. In a machine of the type referred to having a totalizer with a plurality of denominational orders, carry storage elements each associated with a totalizer order and operative when the associated order moves from 9 to 0 in addition and from 0 to 9 in subtraction, check elements each associated with a totalizer order and operable when the associated order stands at 9 after an additive value-entry and at 0 after a subtractive value-entry, interlock members each movable by an operative check element to lock the said storage element of the associated order to that of the next-lower order, and means for driving all totalizer orders associated either with operative storage elements or with storage elements locked by the said interlock members to operate storage elements one step substantially simultaneously in the direction of the value-entry.
- 30 4. Carry device according to claim 1, comprising carry storage rockers each associated with a totalizer order and rockable, when the associated

order moves from 9 to 0 during addition and from 0 to 9 during subtraction, into an operative position in which it remains until after completion of the value-entering operation.

5. Carry device according to claim 1, comprising suitable representations of the 9 and 0 positions of individual totalizer orders, check rockers each associated with a totalizer order and rockable into an operative position when brought into operative association with one of said representations, and means for operatively associating the said check rockers after the value-entering operation with representations of either the 9 positions or the 0 positions of the totalizer orders.

6. In a totalizer of a machine of the type referred to, a carry device comprising carry storage means each associated with a totalizer order and movable, when the associated order moves from 9 to 0 during addition and from 0 to 9 during subtraction, into an operative position in which it remains until after completion of the value-entering operation, representations of the 9 and 0 positions of individual totalizer orders and check means operative when associated with these representations, actuating means for operatively associating the said check means with representations of either the 9 or the 0 positions of the re-

spective totalizer orders, interlock means for locking a carry storage means to that of the next-lower totalizer order when the associated check means is operative, driving members each movable under the control of one of said carry storage means into operative association with the respective totalizer wheel, and a driving actuator adapted to displace all driving members simultaneously a predetermined amount in either of two opposite directions, depending on the direction of the preceding value-entering operation, whereby the driving members if in operative association with the respective totalizer wheels advance the latter additively or subtractively.
